CLAIM

An ornamental design for a digital alarm clock, as shown and described.

DESCRIPTION

FIG. 1 is a front elevational view of my new design;
FIG. 2 is a rear elevational view;
FIG. 3 is a top plan view;
FIG. 4 is a bottom plan view;
FIG. 5 is a left side elevational view;
FIG. 6 is right side elevational view;
FIG. 7 is a top and left front perspective view; and,
FIG. 8 is a top and right front perspective view of the clock in an alternate position.
The broken lines shown in the figures are for illustrative purposes only and form no part of the claimed design.
